ARTICLE ASSEMBLING APPARATUS

Emil E. Meistrup, Western Springs, Ill., assignor
to Western Electric Company, Incorporated,
New York, N. Y., a corporation of New York

Application March 31, 1944, Serial No. 528,859

13 Claims. (Cl. 154—41)

This invention relates to an article assembling apparatus and more particularly to an apparatus for attaching a silk filter to a microphone element.

In the manufacture of some types of microphones, it becomes necessary to place a silk filter over the face of the microphone and to seal it thereto. In attaching this filter in enclosing relationship to the open face of the microphone element, it is necessary for an operator to fold the edges of the silk cover or filter over the periphery of the microphone element and attach it thereto with a piece of adhesive tape. As is obvious, this is a tedious and delicate manual operation.

It is an object of the present invention to provide a simple apparatus for expeditiously assembling articles.

In accordance with one embodiment of the invention, an apparatus for attaching a silk filter to a cylindrical microphone element is provided wherein the cylindrical microphone element with a circular sheet of silk placed against one face of it is inserted between a pair of rotatable clamping elements, one of which is provided with a series of apertures for receiving tucking plungers which are normally spring-pressed to a retracted position. Mounted adjacent one of the clamping elements is a stationary cam engaging the rear end of the tucking plungers for gradually advancing the tucking plungers to tuck the sheet of silk around the edges of the cylindrical microphone element just prior to the engagement of the tucked edges of the silk sheet with an adhesive tape fed over a guide roller into attaching engagement with the silk and periphery of the cylindrical microphone element.

A complete understanding of the invention may be had by reference to the following detailed description when considered in conjunction with the accompanying drawings, wherein

Fig. 1 is a view in perspective of an apparatus embodying the present invention, parts being broken away to conserve space, and taken from a position opposite to that which the operator of the apparatus occupies and showing the clamping elements in their clamping position where they are holding a microphone element and a sheet of silk in position to have tape applied to them;

Fig. 2 is a fragmentary perspective view similar to Fig. 1 except that the apparatus is shown in its inoperative position with the clamping elements separated to receive a sheet of silk and a

microphone element and showing the tape guiding wheel in a retracted position;

Fig. 3 is a plan sectional view taken substantially along the line 3—3 of Fig. 1 in the direction of the arrows showing some details of the clamping element which carries the tucking plungers; and

Fig. 4 is a side elevational view, partly broken away, showing the article assembled in the apparatus.

In the drawings, wherein like reference characters designate the same parts throughout the several views, the apparatus is shown as comprising a base 10 having a pair of clamp supporting standards 11 and 12 and a tape supply standard 13 mounted thereon. The tape supply standard carries a roll 14 of adhesive tape from which tape 15 may be drawn and directed to a guide roller 16. Extending across between the two clamp-supporting standards 11 and 12 is a pivot shaft 17 having pivotally mounted thereon a forked lever 18, within the upper forked end of which the guide roller 16 is mounted for free rotation on a shaft 19. The shaft 19 extends outwardly to the right, as viewed in Figs. 1 and 2, from the right hand side of the lever 18 and has a manually operable cam 20 mounted on its right end to engage the clamp supporting standard 11, through the action of which the lever 18 may be manipulated. The cam 20 has a handle 21 formed integrally with it for operating it. The lever 18 is normally urged to rock clockwise, as viewed in Figs. 1 and 2, by a spring-pressed plunger 22, which is seated in a spring barrel 23 having a compression spring 24 therein for normally urging the plunger 22 upwardly to the right (Figs. 1 and 2). Mounted on the base 10 is a trunnion block 25, in which the spring barrel 23 is pivotally mounted on trunnions 26. Attached to the left end of the forked portion of the lever 18 is a cam rod 27 having a cam 28 formed integrally therewith for engaging and actuating a plunger 29 freely slidable in a projecting portion 30 of the clamp-supporting standard 12. The end of the plunger 29 opposite to that which engages the cam 28 engages a cam plate 31, which is in the form of a split ring having its lower end, as designated at 32, fixed to the standard 12 and having a major portion of it free of the standard 12, whereby, when the plunger 29 is moved to the position shown in Fig. 1 from the position shown in Fig. 2, the cam plate 31 will be flexed to the position shown in Fig. 1 and will provide a sloping cam surface for actuating a series of tucking plungers, designated

generally by the numeral 33. In addition to the cam rod 27, the lever 18 carries a tape guide 35, which is of inverted U-shaped configuration and partially encloses the upper surface of the guide roller 16 to hold a tape 15 in position thereon.

The plungers 33, as seen most clearly in Fig. 3, comprise a shank 40 having a rounded tip 41 and a head 42 also slightly rounded. The plungers 33 are freely slideable in a clamping element, designated generally by the numeral 43, provided with a plurality of apertures 44 adjacent its periphery for receiving the plungers 33. The apertures 44 extend through an annular shoulder 45 of the clamping element 43, which, in addition to the shoulder 45, comprises a shank portion 46 and a reduced portion 47. Each of the plungers 33 has a compression spring 34 surrounding its shank 40 and interposed between the head 42 and the annular shoulder 45 for holding the plunger against the cam plate 31. The reduced portion 47 is journaled in the upper end of the clamp supporting standard 12 and is retained therein by any suitable means, for example, a retaining pin 48, whereas the end of the shank portion bears against the right surface (Fig. 3) of the standard 12. The right surface of the clamping element 43 has a depression 49 formed in it for receiving an extending projection 50 of a cylindrical microphone element 51 clamped between the face of the shoulder portion of the annular shoulder 45 and a reciprocable and rotatable clamping element 52. The clamping element 52 has a collar 54 formed integrally therewith through which a stud shaft 53 may extend into a centrally formed socket 55 in the clamping element 52. The stud shaft 53 has an annular groove 56 formed in it for receiving a pin 57, whereby the clamping element 52 is freely rotatable on the stud shaft 53, but is attached to the shaft for axial movement therewith.

The right hand end of the shaft 53 engages a leaf spring 58, which normally urges the shaft 53 to the left, the spring 58 being attached by means of screws 59 to the clamp supporting standard 11. The upper end of the clamp supporting standard 11 is cut away to provide a cam surface 60, against which the free end of a forked cam lever 61 is urged by the spring 58 due to the fact that the cam lever 61 and shaft 53 are interconnected by means of a pivot pin 62 extending through the shaft 53 and both sides of the forked portion of the forked cam lever. The cam lever 61 is provided with a handle 63, whereby it may be manipulated to retract the shaft 53 from the position shown in Fig. 1 to the position shown in Fig. 2 by moving the handle 63 from the position shown in Fig. 1 to the position shown in Fig. 2, when it is desired to either remove or insert an article to be assembled in the apparatus between the clamping elements 52 and 43.

In the operation of the apparatus, the handle 63 may be moved to the position shown in Fig. 2 to separate the clamping elements 43 and 52 and, thereupon, a microphone element 51 and a sheet 64 of silk may be inserted between the two clamping elements and the handle 63 raised to the position shown in Fig. 1. When the handle 63 is raised to the position shown in Fig. 1, the spring 58 will serve to clamp the microphone element 51 and sheet of silk 64 between the clamping element 52 and the clamping element 43. After the two parts to be assembled are thus positioned between the clamping elements, the handle 21 may be manipulated to permit the spring plunger 22 to force the lever 18 to the position shown in Fig.

1, thereby to carry the guide roller 16 to the position shown in Fig. 1, where the tape 15 on the guide roller will engage the periphery of the microphone element 51. As the lever 18 moves from the position shown in Fig. 2 to the position shown in Fig. 1, the cam 28 pushes the plunger 29 from the position shown in Fig. 2 to the position shown in Fig. 1, thereby compressing some of the springs 34 and forcing the tucking plungers 33 to the position in which they are shown in Fig. 1, thus tucking the edges of the sheet of silk 64 around a portion of the left peripheral edge of the element 51, as clearly illustrated in Fig. 1. Therefore, when the length of tape 15 engages the microphone element 51 and tucked sheet of silk 64, the clamping element 43 may be rotated to apply a layer of adhesive tape to the folded-over or tucked edge of the sheet 64 and the periphery of the microphone element 51, the clamping element 43 being provided with a knurled periphery to facilitate the rotation thereof by the operator. As the clamping element 43 is rotated in a counterclockwise direction, as viewed in Figs. 1 and 2, successive ones of the tucking plungers 33 will ride up the cam plate 31 and will fold the sheet of silk 64 over the edge of the element 51 and just prior to the point where the tape 15 engages the sheet of silk and the element 51, the plungers 33 will drop off of the free end of the cam plate 31, but since the next adjacent plunger will be in its extreme advanced position, the fold formed by the preceding plunger will not be released until it is engaged by the adhesive tape. The operator may make one and a fraction or more wraps of the adhesive tape 15 around the microphone element 51 to secure the sheet of silk in enclosing relation with the end of the element 51 and after a sufficient length of tape 15 has been applied to the assembled parts, the tape wrapped on the assembled parts may be severed from the strip 15 in any suitable manner after retracting the roller 16 from the position shown in Fig. 1 to the position shown in Fig. 2, through the manipulation of the handle 21 and after releasing the clamping elements 51 and 43 from clamping engagement with the assembled parts.

What is claimed is:

1. An apparatus for assembling a relatively flexible sheet on an end of a cylindrical member comprising a pair of rotary clamping members for holding the sheet and member in engagement with each other, a plurality of tucking elements carried by one of said clamping members, means for progressively advancing said tucking elements to fold an edge of the sheet into engagement with the periphery of the cylindrical member, and means for directing an adhesive strip into engagement with the folded edge of the sheet and the periphery of the element.
2. An apparatus for assembling a relatively flexible sheet on an end of a cylindrical member comprising a pair of rotary clamping members for holding the sheet and member in engagement with each other, a plurality of tucking elements carried by one of said clamping members, means for advancing said tucking elements to fold an edge of the sheet into engagement with the periphery of the cylindrical member, means for retracting said elements, and means for directing an adhesive strip into engagement with the folded edge of the sheet and the periphery of the element.
3. An apparatus for assembling a relatively flexible sheet on an end of a cylindrical member com-

prising a pair of rotary clamping members for holding the sheet and member in engagement with each other, a plurality of tucking elements carried by one of said clamping members, a stationary cam for advancing said tucking elements to fold an edge of the sheet into engagement with the periphery of the cylindrical member, means for directing an adhesive strip into engagement with the folded edge of the sheet and the periphery of the cylindrical member, resilient means for urging said directing means to its operative position, and cam means for rendering said stationary cam operative.

4. An apparatus for assembling a relatively flexible sheet on an end of a cylindrical member comprising a pair of rotary clamping members for holding the sheet and member in engagement with each other, a plurality of tucking elements carried by one of said clamping members, a stationary cam for advancing said tucking elements to fold an edge of the sheet into engagement with the periphery of the cylindrical member, means for directing an adhesive strip into engagement with the folded edge of the sheet and the periphery of the cylindrical member, resilient means for urging said directing means to its operative position, cam means for rendering said stationary cam operative, and a common actuator for the directing means and the cam means.

5. An apparatus for assembling a relatively flexible sheet on an end of a cylindrical member comprising a pair of rotary clamping members for holding the sheet and cylindrical member in engagement with each other, a plurality of tucking elements carried by one of said clamping members, a stationary cam for advancing said tucking elements to fold an edge of the sheet into engagement with the periphery of the cylindrical member, means for directing an adhesive strip into engagement with the folded edge of the sheet and the periphery of the cylindrical member, resilient means for urging said directing means to its operative position, cam means for rendering said stationary cam operative, and means for retracting one of said clamping elements from clamping position.

6. An apparatus for assembling a relatively flexible sheet on a member, a flexible camming element, a plurality of plungers for actuation by said camming element to fold the flexible sheet into engagement with a surface of the member, cam means for flexing said camming element to operative position, and rotary means for carrying said plungers in engagement with said camming element.

7. An apparatus for assembling a relatively flexible sheet on a member, a flexible camming element, a plurality of plungers for actuation by said camming element to fold the flexible sheet into engagement with a surface of the member, cam means for flexing said camming element to operative position, rotary means for carrying said plungers in engagement with said camming element, and means for directing an attaching strip to engagement with said surface and folded flexible sheet.

8. An apparatus for assembling a relatively flexible sheet on a member, a flexible camming element, a plurality of plungers for actuation by said camming element to fold the flexible sheet into engagement with a surface of the member, cam means for flexing said camming element to operative position, rotary means for carrying said plungers in engagement with said camming element, and means cooperating with said rotary

means for temporarily clamping the flexible sheet and member into operative association with the plungers.

9. An apparatus for assembling a relatively flexible sheet on an end of a member, a flexible camming element, a plurality of plungers for actuation by said camming element to fold the flexible sheet into engagement with a surface of the member, cam means for flexing said camming element to operative position, rotary means for carrying said plungers in engagement with said camming element, means for directing an attaching strip to engagement with said surface and folded flexible sheet, and a common actuator for said cam means and said directing means.

10. An apparatus for assembling a relatively flexible sheet on a cylindrical member, a flexible camming element, a plurality of plungers for actuation by said camming element to fold the flexible sheet into engagement with a surface of the member, cam means for flexing said camming element to operative position, rotary means for carrying said plungers in engagement with said camming element, means for directing an attaching strip to engagement with said surface and folded flexible sheet, resilient means normally holding said directing means and said cam means in operative position, and a manually operable cam for compressing said resilient means and reTRACTING the directing means and cam means to inoperative position.

11. An apparatus for assembling a round sheet of flexible material on the end of a cylindrical member comprising a flexible camming element, a plurality of plungers for actuation by said camming element to fold the edges of the sheet into engagement with the peripheral surface of the cylindrical member, cam means for flexing said camming element to operative position, rotary means for carrying said plungers in engagement with the camming element, and means for guiding a strip of adhesive tape into engagement with the folded surfaces of the sheet and the peripheral surface of the cylindrical member.

12. An apparatus for assembling a round sheet of flexible material on the end of a cylindrical member comprising a flexible camming element, a plurality of plungers for actuation by said camming element to fold the edges of the sheet into engagement with the peripheral surface of the cylindrical member, cam means for flexing said camming element to operative position, rotary means for carrying said plungers in engagement with the camming element, means for guiding a strip of adhesive tape into engagement with the folded surfaces of the sheet and the peripheral surface of the cylindrical member, and means cooperating with said rotary means to clamp the sheet and cylindrical member in position against the rotary member.

13. An apparatus for assembling a round sheet of flexible material on the end of a cylindrical member comprising a flexible camming element, a plurality of plungers for actuation by said camming element to fold the edges of the sheet into engagement with the peripheral surface of the member, cam means for flexing said camming element to operative position, and rotary means rotatable with the cylindrical member having an annular shoulder for slidably supporting said plungers in position to successively engage the round sheet adjacent its periphery and to carry said plungers in sliding engagement with said camming element.
